UNITED STATES PATENT OFFICE.

JOHANN SEEFRIED, OF NUEREMBERG, GERMANY.

DESIGN FOR A FASTENER FOR PAPER BAGS.

46,513.

Specification for Design.

Patented Oct. 6, 1914.

Application filed November 13, 1913. Serial No. 800,890. Term of patent 3½ years.

To all whom it may concern:

Be it known that I, JOHANN SEEFRIED, a subject of the King of Bavaria, German Empire, residing at Nuremberg, Germany, have invented a new, original, and ornamental Design for Fasteners for Paper Bags, of which the following is a complete specification.

This design relates to a new, original and ornamental fastener for paper-bags; the novelty claimed in the design is the shape of the article, including the cross-sectional curvature, as shown in the accompanying drawing.

The drawing shows my new design for a fastener for paper bags in: Figure 1, as a front plan view, in Fig. 2, as a rear plan view and in Fig. 3, as a section on line C—D of Fig. 2.

I claim:

The ornamental design for a fastener for paper bags as shown and described.

In testimony whereof I affix my signature in presence of two witnesses.

JOHANN SEEFRIED.
